UNITED STATES PATENT OFFICE.

JOHN P. NIKONOW, OF DAYTON, OHIO.

COMBINED LIFTING-JACK AND HOIST.

1,295,357.

Specification of Letters Patent. Patented Feb. 25, 1919.

Application filed September 22, 1917. Serial No. 192,812.

To all whom it may concern:

Be it known that I, JOHN P. NIKONOW, a citizen of Russia, and a resident of the city of Dayton, in the county of Montgomery and State of Ohio, have invented a new and useful Improvement in Combined Lifting-Jacks and Hoists, of which the following is a specification.

My invention relates to a combined lifting jack and hoist and has particular reference to the portable, hand or power operated mechanisms, suitable for carrying in automobiles, trucks and the like.

My invention has for its object to provide a mechanism of the character, above indicated, which is simple in form and efficient in operation, the same apparatus being suitable for raising the load above the ground by jacking it up, for moving the load horizontally and for hoisting it by means of a rope or chain.

There have been employed heretofore, separate apparatus for each of the above mentioned operations, lifting jacks being of such construction, as to render them unsuitable for hoisting work.

I have produced a mechanism which utilizes features of ordinary lifting jacks, and, in addition, has parts, which in combination with the aforesaid features, enable the mechanism to be used as a hoist, winch or capstan.

In the accompanying drawings, Figure 1, is a side elevation of my mechanism, when it is employed as a hoist. Fig. 2 is an end elevation, and Fig. 3 is a detail view of a rope with reinforcements.

The mechanism comprises a stem 37, threaded on the outside and hollow inside. This stem has an enlarged portion constituting a jack head 45, adapted to engage the load, such as an axle of a vehicle, when raising same from the ground.

The stem 37 slides freely in the stand 46 having the foot 47, which is sufficiently large to provide a safe resting base, when mechanism is used as a jack.

The stand 46 has a slot in the upper part, where a gear wheel 38 is located. This gear has a thread on inside, engaging the thread on the stem 37. Therefore, by rotating gear 38, the stem 37 can be raised or lowered. The stem itself, is prevented from rotating through friction with the load engaged.

Thrust from the gear 38 is taken in one direction by the end of the stand 46 and in

the other by the inside surface of the yoke 48 (which is shown as integral with the stand 46). Part of this yoke forms a bearing 40 for an auxiliary shaft 41. On this is mounted another gear wheel 39, engaging gear 38 with any desired ratio. A handle 42 may be used to rotate the gears in either direction.

A yoke 49 is pivotally attached to the stand 46 by a pivot 50 and may be swung around (as shown in dotted lines) so as not to interfere with the stand resting on the ground.

In this way my mechanism can be used as an ordinary lifting jack, such as are used for automobiles, etc.

My mechanism has, however, additional attachments, enabling it to be used as a hoist. These attachments consist in two sets of one way clamps 44 on the stem 45 and 43 on the post 47. These clamps are made to engage the rope 51. Each clamp consists of two oppositely located sections 44 on pivots 53. The engaging surface of a section is made eccentric with the pivot, so that friction with the rope will tighten the grip or hold on this rope, when moved in one direction, and completely release, when moved in the other. Yoke 49 may be swung in direction of lift, and another rope with hook 52 will complete the hoisting mechanism.

When operating as a hoist, the free end of the rope 51 should be attached to the object to be moved (such as an automobile, when it is ditched), and the free end of rope 54 to some stationary object (such as a tree, etc.), or vice versa. The stem should be first moved out of the stand 46 as far as it will go without losing engagement with the gear 38. Rotation of the gears in the proper direction will cause the stem to move inside of the stand. The clamps 44 will grip the rope and will pull it with the stem. The hook end of the rope can be pulled easily through clamps 43.

When the stem is completely moved in, the gears must be rotated in the other direction, until the stem is moved out again. During the raising of stem the pull on the rope will cause the clamps 43 to grip the rope, thus supporting the load stationary in its position, and then, clamps 44 will slide freely along the rope.

Therefore, the action of my mechanism is intermittent, but the total amount of lift is limited only by the length of the rope

51, the action of the clamps being entirely automatic.

Instead of rope, a chain or other suitable carrier may be employed.

- 5 5 Important advantages of the mechanism above described are, that it can be used both, as a hoist and as a lifting jack, being compact and simple to manufacture, that, being used as a hoist, it can move objects 10 through large horizontal or vertical distances, requiring only one man for all its operations.

I claim as my invention:

1. In a device of the character described, 15 the combination, with a stand, a threaded stem movable in said stand and having a head adapted to engage the load when said device is employed for lifting, a threaded gear adapted to actuate the stem and pawls 20 secured in said head and movable with said stem and adapted to engage the load when said device is employed for pulling.

2. In a device of the character described, 25 the combination, with a stand, a hollow threaded stem movable in said stand and having a head adapted to engage the load when said device is employed for lifting, a gear having a threaded portion adapted to actuate the stem and pawls secured in said 30 head movable with said stem and adapted to grip a rope extending through said stem when said device is employed for pulling.

3. In a device of the character described, 35 the combination, with a stand, a hollow threaded stem movable in said stand and having a head adapted to engage the load when said device is employed for lifting, a gear adapted to actuate said stem and a set of opposite pawls attached to said head and 40 movable with said stem and adapted to grip a rope extending through said stem when said device is employed for pulling.

4. In a device of the character described, 45 the combination, with a stand, a threaded stem movable in said stand and having a head adapted to engage the load when said device is employed for lifting, a gear having a threaded bearing adapted to actuate said stem pawls secured in said head and 50 movable with said stem and other pawls

fixed in said stand adapted when said device is employed for pulling to alternately grip a rope extending therebetween as said stem is raised or lowered in said stand.

5. In a device of the character described, 55 the combination, with a stand, a threaded stem movable in said stand and having a head adapted to engage the load when said device is employed for lifting, a gear adapted to actuate said stem axially, pawls secured in said head and movable with said stem and adapted when said device is employed for pulling to grip a rope when said stem is moved in one direction and other pawls 60 fixed in said stand adapted to grip the rope 65 when the stem is moved in the opposite direction.

6. In a device of the character described, 70 the combination, with a stand, a threaded stem movable in said stand and having a head adapted to engage the load when said device is employed for lifting, a gear adapted to actuate said stem, devices secured in said head and movable with said stem and adapted to grip a rope, and a yoke adapted 75 to support one end of said stand when said device is employed for pulling.

7. In a device of the class described, the combination, with a hollow stand, and a lifting stem passing through said stand and having a jack head thereon, said stem being threaded on its outside and having a passage longitudinally therethrough, means coöperating with the threads of said stem to move the stem and jack head longitudinally relative to the stand, a clamp carried by said jack head and constructed to grip and move a rope passing through said stem, a second clamp carried by the foot of the stem and serving to grip and hold the rope, and a 80 yoke pivotally mounted on the stand and to which a second rope may be attached.

In testimony whereof, I have hereunto subscribed my name this twentieth day of September 1917.

JOHN P. NIKONOW.
